US0D1062655S

(12) **United States Design Patent** (10) **Patent No.:** **US D1,062,655 S**
(45) **Date of Patent:** **** Feb. 18, 2025**

(54) **KEYPAD**

(71) Applicant: **Crestron Electronics, Inc.**, Rockleigh, NJ (US)

(72) Inventors: **Sae Jhun**, Bayside, NY (US); **Agnieszka Libson**, River Edge, NJ (US); **Benjamin Slivka**, Hillsdale, NJ (US); **Stan Wisniewski**, Pompton Plains, NJ (US)

(73) Assignee: **Crestron Electronics, Inc.**, Rockleigh, NJ (US)

(**) Term: **15 Years**

(21) Appl. No.: **29/928,035**

(22) Filed: **Feb. 7, 2024**

(57) **CLAIM**

The ornamental design for a keypad, as shown and described.

DESCRIPTION

FIG. 1 shows a top front perspective view of a keypad according to a first embodiment.

FIG. 2 shows a bottom front perspective view thereof.

FIG. 3 shows a front view thereof.

FIG. 4 shows a right side view thereof.

FIG. 5 shows a left side view thereof.

FIG. 6 shows a top view thereof.

FIG. 7 shows a bottom view thereof.

FIG. 8 shows a top front perspective view of a keypad according to a second embodiment.

FIG. 9 shows a bottom front perspective view thereof.

FIG. 10 shows a front view thereof.

FIG. 11 shows a right side view thereof.

FIG. 12 shows a left side view thereof.

FIG. 13 shows a top view thereof; and,

FIG. 14 shows a bottom view thereof.

The broken lines in the figures depict portions of the keypad that form no part of the claimed design.

1 Claim, 10 Drawing Sheets
